UNITED STATES PATENT OFFICE.

ELMER J. BLISS, OF EDGARTOWN, AND EDWARD F. WHITE, OF QUINCY, MASSACHUSETTS,
ASSIGNORS TO REGAL SHOE COMPANY, OF BOSTON, MASSACHUSETTS, A CORPORATION
OF MAINE.

LAST.

No. 914,330.

Specification of Letters Patent.

Patented March 2, 1909.

Application filed January 2, 1909. Serial No. 470,502.

To all whom it may concern:

Be it known that we, ELMER J. BLISS and EDWARD F. WHITE, citizens of the United States, and residents, respectively, of Edgartown, county of Dukes, and Quincy, county of Norfolk, Massachusetts, have invented certain new and useful Improvements in Lasts, of which the following is a specification.

10 This invention relates to lasts employed in the manufacture of boots and shoes and is intended to provide a simple and effective construction by which boots or shoes can be made in a practical manner so as to have a much larger ball measurement or circumference than the measurement at the waist in order that the last may be removed from the shoe without any breaking down or distorting or stretching of the smaller waist portion of the upper through which the ball of the last must pass while being removed, the ultimate purpose being to give the shoe a snug fit about the waist of the foot while giving the larger ball portion of the foot 25 ample opportunity to spread in the shoe while supporting the weight of the wearer.

In the drawings we have illustrated various forms of embodying the principle of this invention.

30 Figure 1 is a side elevation partly in section showing one form of the last. Fig. 2 is a plan view of the same partly in section. Fig. 3 is a detail view of the separable section of the fore part. Fig. 4 is a side elevation partly in section or broken away to show interior parts. Fig. 5 is a plan view of the same partly in section.

The underlying principle of our invention consists in dividing the fore part of the last 40 in the direction of its longitudinal axis by a vertical division, the cut-out portion being completely severed from the other and having a sliding temporary engagement with the main section of the fore part by 45 which the two parts are held together by spring tension when in their normal position for service but are completely separated by the act of withdrawing the main body of the last from the shoe, thereby leaving the separable section to drop out when the shoe is inverted.

In the practice of our invention according to the form shown in the first three figures of the drawings, the last block *a* is severed by

a longitudinal cut as at *a'* extending from the toe along the longitudinal axis of the last to its middle portion, thence laterally to the side of the last back of the ball. The section *b* which fills out this cutaway portion of the last is grooved on its inner longitudinal face to receive a spring metal tongue *b'* which is firmly secured at its forward end in any suitable manner to the inner wall of the slot or groove *b''* but which is inclined rearwardly and outwardly so that its rear end projects some distance beyond the inside wall or face of the section as shown in Fig. 3.

The vertical inside face of the main section *a* is provided with a staple or hook-like device *a''* adapted to receive the spring tongue *b'* to allow the same to have a sliding movement therein. The main portion may also be provided with a guide pin *a''* which projects into the slot *b''* of the separable member. The rear or laterally extended wall of the separable section *b* is provided with a socket *b''* adapted to receive a forwardly projecting guide or holding pin *a''* fixed in the corresponding portion of the main section *a*. As the rear portion of the 80 spring tongue *b* projects outside of the groove so as to engage the co-operating staple *a''*, it is obvious that when the separable section is placed in position to have the rear or free end of the spring tongue 85 enter the staple, the parts are then in position to permit the rearward movement, which owing to the inclination of the spring tongue tends to press the two sections closely together as the separable block assumes its 90 normal position for service. The guide pins *a''* and *a''* engaging the sockets or recesses in the separable section tend to hold the two parts rigidly in operative position to resist external pressure when the shoe is being 95 lasted or otherwise worked upon.

In Figs. 4 and 5 we have shown a somewhat modified form of the invention. In that case the main section *a* of the last block and the separable section *b* are divided as above described but instead of employing a single staple for receiving the spring tongue *b''*, we provide two staples *a''* and *a''* placed astride a wear plate *a''* through both of which the spring tongue is passed. In this case the 100 spring tongue having two points of engagement some distance apart, serves to prevent the displacement of the separable section 105

from its proper operative position relative to the main section. In order to avoid the spreading open of the two sections at the toe portion to enable the laterally projecting 5 guide pin of the main section to pass by the spring tongue, we make this guide pin in the form of a yielding plunger a^3 seated in a socket containing a spring a^7 which normally forces the pin outward into engagement with 10 the recess in the separable block. The outer end of this pin is curved or beveled however, so that when it comes in contact with the spring tongue as the main section is withdrawn, it is pressed back into its socket instead of forcing the two sections apart. To 15 prevent the two sections from adhering or sticking together, we provide a spring-pressed plunger a^8 adapted to press forward normally against the rear face of the separable section b . When the parts of the last 20 are in place in the shoe, the external pressure of the upper keeps this plunger retracted but as soon as the main section is drawn back to give the two sections a chance 25 to separate, the plunger acts to cause this separation. In Fig. 1 we showed the heel portion of the last block joining the main portion without any break or joint. In the form shown in Fig. 4 however, the heel portion 30 of the last is hingedly connected to the main body of the fore part by means of a hinged joint c , a wedge-shaped recess being filled by a wedge-shaped piece c' having sliding engagement with the rear transverse wall 35 of the fore part and the front transverse face of the heel part.

The above described constructions make it possible to build a shoe with a snug-fitting waist portion properly adapted to support 40 the foot and an enlarged ball portion with ample room to allow the ball of the foot to spread inside the shoe and is also capable of satisfying extreme requirements for large ball measure relative to the waist measurement in cases where a bunion or swelling is 45 formed on the ball of the foot as often happens.

What we claim is:—

1. A last for boots and shoes embracing a 50 heel part and a vertically divided fore part, said fore part embracing a main section joining the heel, and a separable side section connected therewith by a sliding connection which permits the main portion to be removed from the shoe, leaving the separable section in place to be removed separately, substantially as described.

2. A last for boots and shoes embracing a 60 heel part and a vertically and longitudinally divided fore part, said fore part embracing a main section joining the heel, and a shorter side section connected therewith by a sliding connection which serves to hold the separable parts together under spring tension while 65 permitting the complete separation of the

parts when the main section is withdrawn from the shoe, substantially as described.

3. A last for boots and shoes embracing a heel part and a vertically and longitudinally divided fore part, said divided fore part embracing a main section joining the heel, and a separable side section connected therewith by a sliding connection which serves to press the parts together under spring tension when they are in normal operative position in the shoe, while permitting the complete separation of the parts when the main section is withdrawn, and means tending to separate or force apart the two sections, substantially as described.

4. A last for boots and shoes embracing a heel part and a vertically divided fore part, said divided fore part embracing a main section joining the heel, and a separable side section connected therewith, one of said sections being provided with a recess, a spring tongue secured in said recess at its forward end and having its rearward end extending obliquely outside of said groove, cooperating means on the other section for engaging said spring tongue to form a sliding and clamping connection between the two parts, substantially as described.

5. A last for boots and shoes embracing a heel part and a vertically and longitudinally divided fore part, said divided fore part embracing a main section joining the heel, and a separable side section, the separable section being provided with a longitudinal recess or groove, a spring tongue secured in said groove at its forward end and extending rearwardly in an oblique direction with its rear end projecting outside of said groove, a cooperating staple secured to the main section to receive said spring tongue, and a guide pin secured to the main section and projecting into the forward part of said groove, substantially as described.

6. A last for boots and shoes embracing a heel part and a vertically and longitudinally divided fore part, said fore part embracing a main section joining the heel, and a separable side section having sliding connection with the main part, one of said sections being formed with a longitudinal recess in its inner 115 face, a spring tongue secured in said recess, the other section being provided with means for slidingly engaging said spring tongue to hold the parts clamped together when in normal position, while permitting their complete separation when the main section is withdrawn, and a spring pressed guide pin secured in one section to engage an oppositely disposed recess in the other section, substantially as described.

7. A last for boots and shoes embracing in its construction a heel portion, a vertically and longitudinally divided fore part hingedly connected with said heel, said fore part comprising a main section joining the heel, and a 130

separable section having sliding connection with the main part by which the two parts are slidably clamped together when in normal position, while permitting the complete separation of the parts when the main part is withdrawn from the shoe, substantially as described.

In witness whereof, we have subscribed the above specification.
